UNITED STATES PATENT OFFICE.

WILLIAM H. CLARKE, OF OLEAN, NEW YORK.

BOTTLE-STOPPER.

SPECIFICATION forming part of Letters Patent No. 314,110, dated March 17, 1885.

Application filed January 16, 1885. (No model.)

To all whom it may concern:

Be it known that I, WILLIAM H. CLARKE, a citizen of the United States, residing at Olean, Cattaraugus county, New York, have invented 5 new and useful Improvements in Bottle-Stoppers, of which the following is a specification.

My invention relates to bottle-stoppers, and the purpose thereof is to provide devices for 10 permanently attaching the stopper to the bottle and for clamping the same in place, the clamping-lever having a double bearing upon the stopper or plug and being guided by the bail or yoke to which it is pivoted or upon 15 which it is supported, whereby the bail prevents the lever from being forced sidewise, guides it into proper position relatively to the stopper, and gives the lever a broad contact upon the latter.

20 My invention consists in the several novel features of construction and combinations of parts hereinafter fully set forth, and definitely pointed out in the claims.

Referring to the drawings, Figure 1 is a vertical central section taken through the stopper and lever. Fig. 2 is a side elevation of the bail and stopper, the lever being detached. Fig. 3 is a perspective view of the cam-lever.

In the said drawings, the reference numeral 30 1 denotes the bottle-neck having the head, 2, usually formed upon all bottles. Upon this head is mounted a yoke or bail, 3, hooking under the head or connected therewith in any suitable manner. This bail is carried above 35 the top of the neck 1, and provided with a central eye, 4, which may be formed by a loop in the wire or by a separate device. In this loop or eye 4 is pivotally mounted a cam-lever, 5, having two parallel branches or forks, 6, one lying upon each side of the bail. The lever is attached to the loop by a pivot-pin, 7, passing through said loop and through both forks 6 of the lever. A back or strip, 8, is mounted upon the parallel plates 6 and prolonged beyond their lower ends to form a 45 thumb-piece, 9.

The stopper 10 is formed of rubber, cork, or other suitable material, and provided with a cap, 11, of metal, wood; or other substance, having opposite lugs or ears, 12, which are 50 perforated to receive the bail, the construction being such that the stopper will readily move up or down upon the bail or yoke, but is not easily detached therefrom.

In use the lever 5 is thrown down until the 55 thumb-piece 9 lies upon one part of the bail. In this position it firmly holds the stopper in place, the two parallel plates 6 of the lever having contact with the cap-plate 11 upon each side of its central point, and thereby holding 60 it securely in place. The cam is guided by the bail into proper position upon and engagement with the stopper by means of the parallel plates of said lever, which lie upon each side of the bail, as shown.

65 This forms a strong, cheap, efficient, and easily-operated device, and one wherein the stopper and its parts are all connected together.

What I claim is—

70 1. In a bottle-stopper, the combination, with a bail or yoke to which the stopper is movably connected, of a cam-lever pivotally mounted upon said yoke, and having parallel plates, which lie upon each side of and are guided by 75 the bail, substantially as described.

2. In a bottle-stopper, the combination, with a bail or yoke having a central eye, in which is pivoted a cam-lever having two parallel plates lying upon each side of said bail, and a stopper having perforated lugs or ears, which engage with the bail, substantially as described.

75 In testimony whereof I affix my signature in presence of two witnesses.

WILLIAM H. CLARKE.
